UNITED STATES PATENT OFFICE.

EDGAR HENRY DODDS, OF STROUD GREEN, ENGLAND.

PIANO-PLAYER ACTION.

1,414,342.

Specification of Letters Patent.

Patented May 2, 1922.

Application filed September 3, 1920. Serial No. 408,011.

To all whom it may concern:

Be it known that I, EDGAR HENRY DODDS, subject of the King of Great Britain and Ireland, residing at 25 Albert Road, Stroud Green, in the county of Middlesex, England, have invented certain new and useful Improvements in Piano-Player Actions, of which the following is a specification.

My invention relates to improvements in the construction of pneumatic actions for automatic musical instruments, piano players and the like, as described in my co-pending patent application No. 333,056, filed October 27th, 1919.

15 The present invention comprises the detailed improvements in the construction of pneumatic actions as described hereafter in conjunction with the accompanying sheet of illustrative drawings in which:—

20 Fig. 1 is a vertical section through a pneumatic action constructed according to the present invention and showing the upper or atmospheric valve open.

25 Fig. 2 is a similar view to Fig. 1 but with the upper or atmospheric valve closed.

Fig. 3 is a plan of the improved pneumatic action.

Fig. 4 is an enlarged detail of the valve chamber and L shaped valve member, and

30 Fig. 5 is a perspective view of a pneumatic showing the valve chamber with the cover plate and valve member removed.

Referring to the drawings the pneumatic 1 of each unit of the pneumatic action is 35 provided with a valve chamber 2 at its inner end, which valve chamber 2 is open upon its upper and rear faces, and these open faces are covered by an L shaped metal plate 3. Packing strips 4 of soft leather or other suit- 40 able material are provided under the edges of this L shaped metal plate so as to ensure an air-tight fit between it and the sides of the valve chamber 2. The upper corners of the sides 5 of the valve chamber 2 are cut away

45 so as to leave spaces 6 for the reception of bearing pins 7 which project on each side of the bent metal valve plate 8. A strip of felt or other suitable material 9 is provided in the space 6 for the bearing pin 7 to rest upon, and 50 the corners of the packing strips 4 where they pass over this space 6 are slit to enable the bearing pin 7 to be inserted into or removed from these spaces.

The bent metal valve plate has upper and 55 lower valve members 10 and 11 which respec-

tively operate to control ports 12 and 13 in the L shaped cover plate 3. The upper port 12 communicates directly to the atmosphere, and a loose valve 14 is secured to the under- 60 side of the cover plate 3 in a position to control the port 12 and adapted to be actuated by the upper valve member 10 of the valve plate 8. This valve 14 comprises a metal plate 15 having a facing of soft leather or other suitable material 16, a portion 17 of which over- 65 laps one edge and is secured to the under face of the L shaped metal plate 3 so as to act as a hinge for the valve 14.

On the back of the metal plate 15 is provided a small disc of felt or other suitable material to form an abutment which rests upon the upper valve member 10 of the hinged valve plate 8.

The lower or vertical valve member 11 is provided with a facing of soft leather or 70 other suitable material 18 and normally bears against the inner vertical face of the L shaped plate 3 so as to close the port 13 communicat- 75 ing with the diaphragm chamber 19 through the passage 20. This diaphragm chamber 19 is formed in one face of the wooden or other 80 block or bar 21 to the front of which each of the units comprising a pneumatic 1 and valve chamber 2 are secured by means of screws 22 passing through the sides 5 of the valve 85 chamber 2 and screwed into the face of the block or bar 21. In order to ensure an air-tight joint between the rear face of the L shaped plate 3 and the front of the block or bar 21, a piece of soft leather or other suitable packing 23 is provided between them.

The diaphragm chamber 21 is closed at its rear by means of a cover 24, upon the face of which is mounted a diaphragm 25 over a small chamber 26 communicating with a pas- 95 sage 27 through the aperture 28. This pas- 90 sage 27 is connected by a flexible tube or other connection from its other end to one of the apertures in the tracker bar so as to admit at- 100 mospheric pressure to the rear side of the diaphragm 25 when the aperture in the track- 105 er bar is uncovered by the music. Suitable packing 29 is provided between the block or bar 21 and its cover 24 so as to ensure an air-tight joint.

The diaphragm 25 consists of a disc of flexible material secured at its edges over the small chamber 26 and at its centre is secured a disc 30 of felt or other suitable material in which is mounted a valve actu- 110

ating pin 31. This valve actuating pin is supported in a cross bar 32 secured to the front face of the diaphragm chamber 19 and extending across the aperture 20. This bar 32 may be of fibre or other suitable material, and acts as a guide to support the valve pin 31, the free end of which is adapted to press against the valve member 11 of the L shaped valve plate 8 so as to force it from its seating to uncover the port 13 and to cause the valve member 10 to press the valve 14 against the upper member of the L shaped plate 3 so as to close the aperture 12 when atmospheric pressure is admitted to the chamber 26 so as to distend the diaphragm 19. This results in the pneumatic 1 being cut off from the atmosphere and placed into communication with the wind chest through the diaphragm chamber 19 so that the pneumatic will be contracted to actuate the piano action.

In order to cause the diaphragm 25 to again return to its normal or deflated position after the pneumatic has been actuated, a small vent or by-pass is provided between the diaphragm chamber 19 and the passage 27 leading to the tracker bar and communicating through the aperture 28 to the chamber 26 upon the other side of the diaphragm. This allows the pressure or suction upon both sides of the diaphragm 25 to be equalized when not in action.

To obtain satisfactory action of the pneumatic it is necessary that this by-pass or vent be regulated with considerable nicety. In order to do this in a simple and effective manner I employ a small tube 33 inserted into the cover 24 so that one end communicates with the diaphragm chamber 19, and a small aperture 34 is provided in its side so as to communicate with the passage 27. In the outer end of this tube 33 is provided a valve pin 35 screw-threaded so as to engage in the outer end of the tube and adapted to be screwed in and out of this tube so that its conical end 36 will operate to control the effective size of the aperture 34 and thus vary the speed with which the pressure or suction upon both sides of the diaphragm 25 will become equalized.

This regulating device is extremely useful in tuning up the action, and since the screwed valve pin 35 may be readily regulated so as to give exactly the effect desired without having to dismantle any of the apparatus, correct tuning of instrument may be quickly and accurately attained.

I claim:—

1. In a pneumatic piano player action, a pneumatic, a valve chamber at one end of the pneumatic, an L shaped plate to close the upper and rear faces of this chamber, packing strips around the edges of the valve chamber over which the L shaped plate is secured, recesses in the sides of the valve

chamber, a hinged valve plate, a pin located in the angle of the valve plate and projecting into the recesses in the sides of the valve chamber, in which it is secured by the L shaped cover plate. 70

2. In a pneumatic piano player action, a pneumatic, a valve chamber at one end of the pneumatic, an L shaped plate to close the upper and rear faces of this chamber, packing strips around the edges of the valve chamber over which the L shaped plate is secured, recesses in the sides of the valve chamber, a hinged valve plate, a pin located in the angle of the valve plate and projecting into the recesses in the sides of the valve chamber, in which it is secured by the L shaped cover plate, a separate valve hinged on the under face of the L shaped cover plate, a facing of soft material to this valve, a projecting edge to the soft material, secured to the cover plate and forming a hinge for the valve, a disc of felt on the back of the valve adapted to butt upon the face of L shaped valve plate, the upper member of the cover plate having an aperture adapted to be closed by this valve when the L shaped valve plate is actuated. 85 90

3. In a pneumatic piano player action, a pneumatic, a valve chamber at one end of the pneumatic, an L shaped plate to close the upper and rear faces of this chamber, packing strips around the edges of the valve chamber over which the L shaped plate is secured, recesses in the sides of the valve chamber, a hinged valve plate, a pin located in the angle of the valve plate and projecting into the recesses in the sides of the valve chamber, in which it is secured by the L shaped cover plate, facing material on the lower member of the valve plate, an aperture in the lower member of the cover plate normally closed by this facing on the lower member of the valve plate, a diaphragm, one side of which is in communication with the tracker bar and the other with the suction or wind chest, and a pin on this diaphragm adapted to actuate the valve plate. 100 105 110

4. In a pneumatic piano player action, a pneumatic, a valve chamber at one end of the pneumatic, an L shaped plate to close the upper and rear faces of this chamber, packing strips around the edges of the valve chamber over which the L shaped plate is secured, recesses in the sides of the valve chamber, a hinged valve plate, a pin located in the angle of the valve plate, and projecting into the recesses in the sides of the valve chamber, in which it is secured by the L shaped cover plate, a separate valve hinged on the under face of the L shaped cover plate, a facing of soft material to this valve, a projecting edge to the soft material secured to the cover plate and forming a hinge for the valve, a disc of felt on the back of the valve adapted to butt upon the face of L shaped 115 120 125 130

valve plate, and an aperture in the upper member of the cover plate adapted to be closed by this valve when the L shaped valve plate is actuated, facing material on 5 the lower member of the valve plate, an aperture in the lower member of the cover plate normally closed by this facing on the lower member of the valve plate, a diaphragm one side of which is in communication 10 with the tracker bar and the other with the suction or wind chest, and a pin on this diaphragm adapted to actuate the valve plate.

5. In a pneumatic piano player action, a 15 pneumatic, a valve chamber at one end of the pneumatic, an L shaped plate to close the upper and rear faces of this chamber, packing strips around the edges of the valve chamber over which the L shaped plate is 20 secured, recesses in the sides of the valve chamber, a hinged valve plate, a pin located in the angle of the valve plate, and projecting into the recesses in the sides of the valve chamber, in which it is secured by the 25 L shaped cover plate, facing material on the lower member of the valve plate, an aperture in the lower member of the cover plate normally closed by this facing on the lower member of the valve plate, a diaphragm one 30 side of which is in communication with the tracker bar and the other with the suction or wind chest, and a pin on this diaphragm adapted to actuate the valve plate, a vent passage connecting the two sides of the dia- 35 phragm, a screw-threaded valve pin in the vent passage and adapted to be screwed in or out to control the passage of air through the vent to regulate the action of the pneumatic.

6. In a pneumatic piano player action, a 40 pneumatic, a valve chamber at one end of the pneumatic, an L shaped plate to close the upper and rear faces of this chamber, packing strips around the edges of the valve chamber over which the L shaped plate is 45 secured, recesses in the sides of the valve chamber, a hinged valve plate, a pin located in the angle of the valve plate and projecting into the recesses in the sides of the valve chamber, in which it is secured by the 50 L shaped cover plate, a separate valve hinged on the under face of the L shaped cover plate, a facing of soft material to this valve, a projecting edge to the soft material, secured to the cover plate and forming a hinge for the valve, a disc of felt on the back of the valve adapted to butt upon the face of L shaped valve plate, and an aperture in the upper member of the cover plate adapted to be closed by this valve 60 when the L shaped valve plate is actuated, facing material on the lower member of the 65 valve plate, an aperture in the lower member of the cover plate normally closed by this facing on the lower member of the valve plate, a diaphragm one side of which is in communication with the tracker bar and the other with the suction or wind chest, and a pin on this diaphragm adapted to 70 actuate the valve plate, a vent passage connecting the two sides of the diaphragm, a screw-threaded valve pin in the vent passage and adapted to be screwed in or out to control the passage of air through the vent to regulate the action of the pneumatic.

EDGAR HENRY DODDS.
